PORTABLE SHAMPOO CABINET

Georgia E. Glintz, Des Moines, Iowa

Application July 7, 1954, Serial No. 441,830

3 Claims. (Cl. 4—159)

This invention relates in general to beauty parlor equipment and more specifically to a portable shampoo cabinet.

There are many persons who are confined to their beds and accordingly are unable to properly position themselves relative to a water supply in a sink or basin whereby a proper shampoo can be given. It is therefore the primary object of this invention to provide an improved shampoo cabinet which is of such a nature whereby it may be utilized to easily give a shampoo to a person while lying in bed.

Another object of this invention is to provide an improved portable shampoo cabinet, the cabinet being mounted on a portable frame and being vertically adjustable with respect thereto in order that the basin and cushion of the shampoo cabinet may be properly vertically positioned with respect to the bed or other article of furniture on which the person whose hair is to be shampooed is resting.

Another object of this invention is to provide an improved portable shampoo cabinet which is so constructed whereby it carries its own water supply and has accommodations for receiving the used water.

A further object of this invention is to provide an improved portable shampoo cabinet which is self-contained, easily adjusted to a person's head while such person is lying in bed, and is very attractive in appearance.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a front elevational view of the shampoo cabinet which is the subject of this invention and shows the same with the doors thereof open in order to clearly illustrate the relationship of water tanks disposed therein;

Figure 2 is an exploded perspective view of the shampoo cabinet of Figure 1 and shows the same with a top cover thereof removed whereby access to the interior of the cabinet may be obtained from the top thereof;

Figure 3 is an enlarged vertical sectional view taken through the shampoo cabinet in the basin portion thereof and shows the relationship of the various parts of the shampoo cabinet with respect to a person having her hair washed, a portion of the person and the bed on which she is resting being illustrated;

Figure 4 is a transverse horizontal sectional view taken substantially upon the plane indicated by the section line 4—4 of Figure 3 and shows the arrangement of both the drain tank of the shampoo cabinet and the supports for retaining a water supply tank thereof in an elevated position such as that of Figure 3;

Figure 5 is a fragmentary vertical sectional view taken substantially upon the plane indicated by the section line 5—5 of Figure 3 and shows the details of a support for retaining the water supply tank in a vertically adjusted position; and

Figure 6 is an enlarged fragmentary vertical sectional

2

view taken substantially upon the plane indicated by the section line 6—6 of Figure 4 and shows the manner in which the support of Figure 5 is retained in an adjusted vertical position.

5 Referring now to the drawings in detail, it will be seen that the portable shampoo cabinet which is the subject of this invention includes a frame which is referred to in general by the reference numeral 10. The frame 10 includes an elongated one-piece metal which is so bent as 10 to form a pair of spaced vertical legs 12 at opposite ends thereof. Integral with each of the legs 12 is a downwardly and forwardly sloping portion 14 which terminates in a lowermost rearwardly directed portion 16. Connecting together the rearward portions 16 is a lower horizontal portion 18. The horizontal portion 18 is braced with respect to the sloping portions by suitable V-braces 20. As is best illustrated in Figure 1, carried by the horizontal portion 18 is a pair of transversely spaced wheels 22.

Carried by the frame 10 is a generally rectangular cabinet which is referred to in general by the reference numeral 24. The cabinet 24 includes a rear wall 26, a pair of side walls 28, a front wall panel 30 and a bottom wall 32. The cabinet 24 also includes a removable cover 34 which has a handle 36 to facilitate the removal thereof.

20 25 The cabinet 24 is provided with a transverse partition 38 which divides the cabinet into a pair of spaces. Access to the two spaces is provided by a pair of doors 40 hinged by the front wall panel 30 in closing access openings 42 therein.

30 Secured to the rear wall 26 of the cabinet 24 in spaced relation is a pair of vertically disposed sleeves 44. The sleeves 44 have their upper ends connected together by a handle forming member 46. The sleeves 44 are telescoped over the vertical frame members 12 and are retained in vertically adjusted positions by a set screw 48. Thus the cabinet 24 may be retained in a vertically adjusted position with respect to the floor or supporting surface on which the frame 10 is disposed.

35 Disposed within the lower part of one half of the cabinet 40 45 50 55 60 65 70 75 80 85 90 95 100 105 110 115 120 125 130 135 140 145 150 155 160 165 170 175 180 185 190 195 200 205 210 215 220 225 ported by standards 78 disposed at the corners thereof. The standards 78 have their lower portions received in sleeves 80 rigidly secured in the corners of the half of the cabinet 24 with which they are associated, as is best illustrated in Figure 4. The support 70 is retained in a vertically adjusted position by set screws 82 carried by the sleeves 80 and engaging the standards 78.

As is best illustrated in Figure 3, the water supply tank 64 includes an outlet 84 which is controlled by a valve 86. Secured to the outlet 84 is a length of flexible tubing 88 which is provided at its opposite end with a spray head 90.

When it is desired to utilize the portable shampoo cabinet which is the subject of this invention, the shampoo cabinet is wheeled along side a bed, such as the bed 92 on which a person who is bedridden is lying. The person is then suitably positioned on the bed 92 with his or her head 94 resting upon a cushion 96. The cushion 96 is removably carried by the upper part of the cabinet 24 in alignment with the basin 58 and extends outwardly therefrom so as to rest upon the bed 92, as is best illustrated in Figure 3. It is to be understood that the cabinet 24 must be properly vertically adjusted through the use of the set screws 48.

After the person whose head is to be washed is properly positioned with respect to the cabinet 24, the valve 86 is then opened to supply the water to the spray head 90 so that water may be supplied to the person's head 94. The water then drains into the basin 58 from where it goes into the drain tank 50. After the shampooing operation is over, the drain tank 50 is removed from the cabinet 24 and emptied. The water supply tank 64 is then placed back into the cabinet 24 and the support 70 therefor is lowered into its normal position. Finally, the cover 34 is again repositioned and the shampoo cabinet may then be readily wheeled away either for storage or for further use.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly, all suitable modifications and equivalents

may be resorted to, falling within the scope of the appended claims.

What is claimed as new is as follows:

1. A portable shampoo cabinet comprising a portable frame, a cabinet carried by said frame, a basin carried by said cabinet in the upper part of one half thereof, a water supply tank in the other half of said cabinet, a drain tank underlying said basin and receiving drain water therefrom, and adjusting means for said cabinet for vertically adjusting said cabinet to facilitate proper vertical positioning of said basin, said adjustable means including a pair of tubular sleeves connected at top end portions by a horizontal handle member, a pair of leg members vertically adjustably secured within the other end of said sleeves, said legs including a forwardly sloping portion terminating in a rearwardly directed portion, each of which being connected to a rear horizontal portion, and a pair of spaced wheels journaled on said rear horizontal portion.

2. A portable shampoo cabinet comprising a portable frame, a cabinet carried by said frame, a basin carried by said cabinet in the upper part of one half thereof, a water supply tank in the other half of said cabinet, a drain tank underlying said basin and receiving drain water therefrom, said water supply tank being removable to facilitate filling of the same, and a vertically adjustable support for said water supply tank, said water supply tank being stored under said support.

3. A portable shampoo cabinet as set forth in claim 2 wherein said vertically adjustable support comprises sleeves vertically supported in the portion of the cabinet in which the tank is stored, standards adjustably supported in said sleeves, and a tank supporting member carried by said standards.
